US0D1008667S

(12) **United States Design Patent** (10) **Patent No.:** **US D1,008,667 S**
(45) **Date of Patent:** **** Dec. 26, 2023**

(54) **MAKEUP BRUSH**

(71) Applicant: **And.B, LLC**, New York, NY (US)

(72) Inventors: **Bobbie Lynn Grund**, New York, NY (US); **Andrea DeVos Abraham**, New York, NY (US)

(73) Assignee: **Woosh Beauty, LLC**, Grand Rapids, MI (US)

(**) Term: **15 Years**

(21) Appl. No.: **29/716,097**

(22) Filed: **Dec. 6, 2019**

Related U.S. Application Data

(63) Continuation of application No. 29/644,792, filed on Apr. 20, 2018, now Pat. No. Des. 869,174, which is a continuation of application No. 29/573,881, filed on Aug. 10, 2016, now Pat. No. Des. 818,275.

(57) **CLAIM**

The ornamental design for a makeup brush, as shown and described.

DESCRIPTION

FIG. 1 is a top right perspective view of a makeup brush showing our new design;

FIG. 2 is a right side elevation view thereof;

FIG. 3 is a front elevation view thereof;

FIG. 4 is an inverted left side elevation view thereof;

FIG. 5 is a rear elevation view thereof;

FIG. 6 is a top plan view thereof; and,

FIG. 7 is a bottom plan view thereof.

The broken lines in the figures depict portions of the makeup brush that form no part of the claimed design.

1 Claim, 3 Drawing Sheets
